UNITED STATES PATENT OFFICE

2,524,188

TOW SKIFF

John Edward Christie, Miami Beach, Fla.

Application June 21, 1948, Serial No. 34,239

6 Claims. (Cl. 114—44)

1

The present invention relates to a tow skiff and it consists in the combinations, constructions and arrangements of parts herein described and claimed.

It is an object of the present invention to provide a tow skiff which is simple in its construction and operation yet effective and efficient in use.

Another object of the invention is the provision of a novel hull structure in a skiff of the character set forth.

Another object of the invention is to provide a novel crane structure forming a part of the invention.

Another object of the invention is the provision of a craft which is provided with great maneuverability and which may have great utility as a tugboat.

A further object of the invention is the provision of a novel seagoing craft which is especially adaptable for use in rescue work at sea.

A still further object of the invention is to provide a skiff of the character set forth which is provided with means for encompassing a portion of another craft and with means whereby the latter may be wholly or partially supported.

Another object of the invention is to provide a novel arrangement in a tow skiff of a bridge and a power plant both forming a part of the invention.

Other and further objects of the invention will become apparent from a reading of the following specification taken in conjunction with the drawings, in which:

Figure 1 is a side elevational view of an embodiment of the invention.

Figure 2 is a plan view thereof, and

Figure 3 is a front elevational view of the skiff shown in Figures 1 and 2.

Generally there is provided a tow skiff comprising a pair of spaced longitudinally extending pontoons interconnected at their rear ends with a transversely extending plate to thus form a substantially U-shaped enclosure with the open end thereof at the bow of the skiff. The transversely extending plate is decked and has mounted thereon an elevated bridge whereon the controls are located. The longitudinal pontoons are also interconnected with an elevated crane framework and centrally disposed upon the bridge there is provided an extensible connection for craft which may be placed within the enclosure. Abaft the transversely extending plate is a centrally disposed rearwardly extending boat hull containing a power plant and the rear end

2

of the boat hull and the ends of the transversely extending plate are interconnected with tubular frameworks upon which are supported a fuel tank, tool lockers and the like.

5 Referring more particularly to the drawings, there is shown therein a tow skiff comprising a pair of spaced longitudinally extending pontoons 10 and 11 which each have their forward ends provided with bows 12 and 13, respectively, and

10 whose rear portions are interconnected by a transversely extending plate 14 upon which is fastened decking 15. The plate 14 and decking 15 are additionally reinforced by means of downwardly extending front and rear webs A and B

15 respectively, which are suitably secured as by welding, riveting or the like to the inner side walls of the pontoons 10 and 11. The bottom edge of the reinforcing webs is curved as indicated at C and is spaced above the level of the water so as to eliminate any drag or resistance caused by contact with the water during the travel of the skiff. The curvature C is designed to allow the water to pass under the skiff when operating in either rough or quiet waters.

20 25 Interconnecting each end of the decking 15 and the upper rear portions of the pontoons 10 and 11 are brace plates 16 and 17 which are shaped to conform with the contour of the upper portion of the pontoons.

30 35 Supported by tubular legs 18 affixed to the decking 15 is a transversely extending bridge 19 provided with a ladder 20 communicating with the deck 15. A steering wheel 21 and navigational instruments 22 are situated in the bridge 20.

35 40 Base plates 23 and 24 are fixed forwardly on the pontoons 10 and 11, respectively, for the support of pairs of upwardly converging legs 25 and 26, respectively. Amidships on each of the pontoons 10 and 11 is a base plate 27 and 28, respectively, for the support of upwardly converging legs 29 and 30, respectively.

45 50 Supported by the upper ends of the legs 25 and 26 is a transversely extending beam 31 and supported by the upper ends of the legs 29 and 30 is a transversely extending beam 32. Interconnecting the centers of the beams 31 and 32 is a longitudinally extending beam 33 centrally disposed upon which is a pulley housing 34 for a hoist.

55 A winch 35 is affixed centrally and forwardly on the deck 15 and is provided with a cable 36 and hook 37.

A boat hull 38 extends rearwardly from the center of the plate 14, contains a power plant 39

and is provided with a hatch 40 hinged, as indicated at 41, and provided with a handle 42. A rudder 43 is mounted at the rear of the hull 38.

Interconnecting the outer ends of the rear wall of the plate 14 and the rear end of the boat hull 38 is a pair of tubular reinforcing members 44 and 45.

A pair of substantially circular frame members 46 and 47 are connected with the member 45 and with the hull 38 and plate 14, respectively, and support therein a cylindrical fuel tank 48.

Tubular support members 49 and 50 interconnect the member 44 and the plate 14 and the boat hull 38, respectively, and are, in turn, interconnected with a strap 51 and a platform 52 upon which is supported a tool locker 53.

While bolts are shown in the drawings for various connections and fastenings of one part to another, it will be understood that welding, riveting or other means may readily be utilized instead of bolting.

In use it will be apparent that the tow skiff herein described may be used for a variety of purposes. For example a small craft in distress may be wholly or partially encompassed by the pontoons 10, 11 and deck 15 and thereafter be wholly or partially supported by a crane, block and tackle or the like suspended from the beam 33 while the stern of the disabled craft may be held against forward lurching by means of the winch 35 through the cable 36 and 37. The elevated bridge allows for a clear perspective of the operation of the skiff.

While but one form of the invention has been shown and described herein, it will be readily apparent to those skilled in the art that many minor modifications may be made without departing from the spirit of the invention or the scope of the appended claims.

What is claimed is:

1. A tow skiff comprising a pair of spaced longitudinally extending pontoons, a transversely extending plate interconnecting the rear portions of the longitudinal pontoons, a centrally disposed boat hull extending rearwardly of the transversely extending plate, a power plant in said boat hull, a deck upon the transversely extending plate, an elevated bridge supported upon the deck and a crane frame interconnecting the longitudinal pontoons.

2. A tow skiff comprising a pair of spaced longitudinally extending pontoons, a transversely extending plate interconnecting the rear portions of the longitudinal pontoons, a centrally disposed boat hull extending rearwardly of the transversely extending plate, a power plant in said boat hull, a deck upon the transversely extending plate, brace plates secured to and having the contour of the upper portions of the rear of the longitudinal pontoons and affixed to the deck, an elevated bridge supported upon the deck and a crane frame interconnecting the longitudinal pontoons.

3. A tow skiff comprising a pair of spaced longitudinally extending pontoons, a transversely extending plate interconnecting the rear portions

of the longitudinal pontoons, a centrally disposed boat hull extending rearwardly of the transversely extending plate, a power plant in said boat hull, a deck upon the transversely extending plate, an elevated bridge supported upon the deck, two pairs of upwardly converging legs affixed to each of the longitudinal pontoons, a pair of transversely extending beams supported at the upper ends of said legs, a centrally disposed longitudinally extending beam interconnecting the transverse beams and means for supporting hoisting apparatus on the longitudinal beam.

4. A tow skiff comprising a pair of spaced longitudinally extending pontoons, a transversely extending plate interconnecting the rear portions of the longitudinal pontoons, a centrally disposed boat hull extending rearwardly of the transversely extending plate, a power plant in said boat hull, a deck upon the transversely extending plate, an elevated bridge supported upon the deck, a crane frame interconnecting the longitudinal pontoons, a winch centrally and forwardly disposed upon the deck and a hook and cable for the winch.

5. A tow skiff comprising a pair of spaced longitudinally extending pontoons, a transversely extending plate interconnecting the rear portions of the longitudinal pontoons, a centrally disposed boat hull extending rearwardly of the transversely extending plate, a power plant in said boat hull, a deck upon the transversely extending plate, an elevated bridge supported upon the deck, two pairs of upwardly converging legs affixed to each of the longitudinal pontoons, a pair of transversely extending beams supported at the upper ends of said legs, a centrally disposed longitudinally extending beam interconnecting the transverse beams, means for supporting hoisting apparatus on the longitudinal beam, a winch centrally and forwardly disposed upon the deck and a hook and cable for the winch.

6. A tow skiff comprising a pair of spaced longitudinally extending pontoons, a transversely extending plate interconnecting the rear portions of the longitudinal pontoons, a centrally disposed boat hull extending rearwardly of the transversely extending plate, a power plant in said boat hull, a deck upon the transversely extending plate, an elevated bridge supported upon the deck, a crane frame interconnecting the longitudinal pontoons and tubular brace members interconnecting the rear end of the boat hull and the rear ends of the transversely extending plate.

JOHN EDWARD CHRISTIE.
